COIN METER WITH RESET SWITCH CAM

Harry Greenwald, Blauvelt, N. Y., assignor to
 Robco Corporation, New York, N. Y., a corpora-
 tion of New York

Application March 7, 1950, Serial No. 148,164

5 Claims. (Cl. 161—1)

1

This invention relates to new and useful im-
 provements in coin meters with reset switch cams.

When time is left in a meter without a reset
 feature the next person when inserting a coin
 only receives the time that has been left over by
 the former user. A meter with a reset switch
 cam resets the meter to start from zero and gives
 a new and complete cycle for each insertion of a
 coin no matter where the cycle is when the new
 coin is inserted.

The dominating object of this invention resides
 in the construction of a coin meter with a reset
 switch cam which is of extremely simple con-
 struction, efficient and reliable in operation, and
 which may be manufactured and sold at a rela-
 tively low cost. It is proposed to characterize the
 new meter by a switch cam adjustably mounted
 on a gear turnably mounted on a movable mem-
 ber movable back and forth in order that said
 gear may mesh with and may be moved out of
 mesh from a clock driven gear.

It is an object of this invention to adjustably
 mount said switch cam on said gear with the use
 of a clamp screw or other similar simple clamping
 means, by which the cam may be fixed in selected
 adjusted positions for varying the available tim-
 ing of the meter.

Another object of this invention resides in the
 provision of resilient means for urging the first
 mentioned gear into a starting position in order
 that when it is disengaged from the second named
 gear it will immediately turn back to its starting
 position.

Still another object of this invention resides in
 mounting a switch for controlling an electric cir-
 cuit on the movable member previously men-
 tioned, which switch is provided with an operator
 for opening the circuit when lifted from normal
 position, and it is proposed to so arrange the
 switch cam to lift said operator to actuate said
 switch.

Another object of this invention resides in the
 provision of coin operated means for moving the
 movable member to a back position for each coin
 passing through the chute of the meter for sep-
 arating the prior mentioned gears so that the
 resilient means may move the first named gear
 to its starting position. This resets the meter.

For further comprehension of the invention,
 and of the objects and advantages thereof, refer-
 ence will be had to the following description
 and accompanying drawing, and to the appended
 claims in which the various novel features of the
 invention are more particularly set forth.

In the accompanying drawing forming a ma-
 terial part of this disclosure:

2

Fig. 1 is a front elevational view of a coin meter
 with reset switch cam constructed in accordance
 with this invention, the meter being illustrated
 without cover so that the works may be seen.

Fig. 2 is a plan view of the works of the meter
 shown in Fig. 1.

Fig. 3 is a sectional view of the works of the
 meter taken on the line 3—3 of Fig. 1.

Fig. 4 is a schematic wiring diagram of the
 10 coin meter and the appliance which it controls.

The coin meter with reset switch cam, in ac-
 cordance with this invention, includes a casing 10
 having a coin slot 11. A support 12 is mounted
 in said casing 10 with several screws 13. This
 15 support 12 is provided with a coin chute 14
 aligned with said coin slot 11. The support 12
 is formed from a back plate 15, a front plate 16
 held spaced from the back plate 15 by spacer
 strips 17, and these parts being joined together
 in a fixed unit with rivets 18. The space between
 the spacer strips 17 form the chute 14.

A movable member 20 is movably mounted on
 the support 12 to move back and forth. More
 particularly, the movable member 20 is pivotally
 20 mounted on a pintle 21 mounted on and project-
 ing from the support 12. This movable member
 20 is in the nature of a plate movable in a plane
 parallel to the face of the support 12.

A gear 22 is turnably mounted on said movable
 member 20. A stop 23 is mounted on and projects
 30 from the gear 22 and is cooperative with a stop
 24 mounted on and projecting from the movable
 member 20 for limiting turning of the gear 22
 to and from a starting position. As illustrated
 in Fig. 1, the gear 23 is in its starting position
 35 with the stop 23 to the left and against the
 stop 24.

A switch 26 for controlling an electric circuit
 27 is mounted on the movable member 20. This
 switch 26 is provided with an operator 28 for
 40 opening said circuit 27 when lifted from normal
 position. The operator 28 is in the nature of a
 leaf spring which may flex upwards and down-
 wards. A small arcuate leaf spring 29 connects
 with the operator 28 and with another leaf spring
 45 30 provided with a contact engageable with a
 contact on an arm 31. Normally, said contacts
 engage each other. However, when the operator
 28 is lifted the arm 30 will be flexed downwards
 by the small spring 29 so as to open the switch 26.

50 A switch cam 33 is adjustably mounted on the
 gear 22 for lifting said operator 28 to actuate said
 switch 26. This switch cam 33 comprises an in-
 sulation plate turnably mounted concentric with
 the gear 22. The switch cam 33 is provided with
 55 an arcuate slot 34 concentric with the gear 22.

A small clamp screw 35 is mounted on the gear 22 and engages through the slot 34 by which the switch cam 33 is locked in adjusted turned positions upon the gear 22. The gear 22 is imprinted with a scale 36 across which the side 37 of the switch cam 33 passes when the cam 33 is adjusted on the gear 22. This scale 36 is calibrated to indicate different periods of time required for the switch cam 33 to reach and lift the spring operator 28. This controls the timing of the meter.

The coin meter is provided with a gear train which includes said gear 22 and a gear 39 turnably mounted on the support 12. The gear train 22, 39 is driven by a clock drive 40 including an electric clock 41 controlled by said circuit 27. This clock drive functions to turn the gear 22 and in this way turns the switch cam 33 to lift the operator 28.

The gear 22 is associated with resilient means for urging it into its starting position. This resilient means comprises a tension spring 42 having one end attached to a pin 43 mounted on the support 12 and having its other end attached to a pin 44 eccentrically mounted upon the gear 22 in a position so that the spring 42 turns the gear 22 counter-clockwise and causes the stop 23 to engage the stop 24. The spring 42 also acts as resilient means for urging the movable member 20 into a front position in which the gears 22 and 39 mesh with each other. A pin 45 is mounted on the support 12 and acts as a stop for the movable member 20 when it is in a front position in which the gear 22 meshes with the gear 39.

The movable member 20 may be moved to a back position by coin operated means operated by each coin passing through said chute 14 for separating the gears 22 and 39 in order that said resilient means, namely, the spring 42, may move said gear 22 to its starting position to reset the meter. This coin operated means includes a pin 47 mounted on the movable member 20 and engaging an opening 48 in the support 12 so as to engage into the chute 14. A disc 49 is rotatively mounted by a pintle 50 upon the support 12. A plunger 51 is eccentrically connected with the disc 49 by which the disc 49 may be turned. A tension spring 52 is connected with a pin 53 eccentric on the disc 49 and with another pin 54 mounted upon the support 12. This spring 52 normally holds the disc 49 in a normal position.

The disc 49 is also provided with a pin 55 which in said normal position is in the bottom end of an arcuate slot 56 formed through the support 12. This pin 55 extends through the chute 14 and is capable of supporting a coin dropped down into the chute. The chute 14 is provided with a curved projecting member 57 capable of guiding the coin passing down through the chute 14 laterally against the pin 47. The side of the chute 14 opposite the projecting member 57 is formed with a recess 58 through which the coin passes. An electric appliance 60 is shunted across the electric clock 41.

The operation of the coin meter with reset switch cam may be understood from the following:

The meter is illustrated in Fig. 1 with the switch 26 closed. Current is therefore flowing through the circuit 27 operating the clock 41 and the appliance 60. The clock 41 drives the gear 39 which in turn drives the gear 22. The gear 22 will turn clockwise and after a predetermined period of time the cam 33 will engage the operator 28 of the switch 26 and lift said operator to cause the switch 26 to open. The period of time may be

varied by loosening the clamp screw 35 and turning the switch cam 33 backwards or forwards and setting it in a new position as desired. The new position may be easily selected by setting the side 37 of the cam 33 upon a selected marking on the scale 36.

When the switch cam 33 lifts the operator 28 the switch 26 is open and opens the circuit 27 through the clock 41 and the appliance 60 so that both the clock and appliance stop working. To restart the appliance it is necessary that a coin be dropped in the coin slot 11. An important feature of this meter resides in the fact that it is not necessary to wait for an old cycle to be finished before inserting a new coin. No matter where the old cycle is at, if a new coin is inserted the meter will give a complete new cycle from zero.

The coin will fall down the chute 14 and come to rest upon the pin 55. The plunger 51 may now be depressed so as to turn the disc 49 so that the pin 55 moves to the high part of the slot 56. In this latter position it will be against the side of the coin which has now dropped down and come to rest upon the curved projecting member 57 and against the pin 47. When the plunger 51 is now released the spring 52 turns the disc 49 back to its original position so that the pin 55 forces the coin against the pin 47 moving the movable member 20 towards the right, which is considered its back position. The coin then rolls around the projecting member 57 and discharges out of the bottom of the coin chute into a coin box, not illustrated on the drawing.

When the coin moved the pin 47 towards the right it correspondingly moved the movable member 20. Since the gear 22 is carried by the movable member 20, the gear 22 was moved out of mesh with the gear 39. The spring 42 instantly turns the gear 22 counter-clockwise to its starting position in which the stop 23 on the gear 22 engages the stop 24 in the movable member 20. Even though an old cycle is not completed and gear 22 has not as yet reached the position in which the operator 28 opens switch 26, a new coin causes the gear 22 to instantly assume its starting position. When the gear 22 turns to its starting position the cam 33 drops the operator 28 and the switch 26 closes if the cam 33 reached a position in which the operator 28 was raised. After the coin has passed, the pin 47 is released so that the spring 42 pivots the movable member to its front position, that is, towards the left, to a position in which the gear 22 remeshes with the gear 39. Since the switch 26 is now closed the clock 41 and the appliance 60 start operating under a new and complete cycle which will run to its end unless interrupted by the insertion of a new coin.

While I have illustrated and described the preferred embodiment of my invention, it is to be understood that I do not limit myself to the precise construction herein disclosed and the right is reserved to all changes coming within the scope of the invention as defined in the appended claims.

Having thus described my invention, what I claim as new and desire to secure by United States Letters Patent is:

1. A coin meter with reset switch cam, comprising a casing, a support mounted in said casing, a movable member movably mounted on said support to move back and forth, a gear turnably mounted on said movable member, cooperative stops on said gear and said movable member for representing a starting position for turning of

said gear, a switch for controlling an electric circuit mounted on said movable member and having an operator for opening said circuit when lifted from normal position, a switch cam adjustably mounted on said gear for lifting said operator to actuate said switch after said gear has turned a predetermined amount, a gear train including said gear and a gear mounted on said support, clock means having an electric clock controlled by said circuit for driving said gear train for turning said switch cam to lift said operator after said gear has turned a predetermined amount, resilient means for urging said first named gear to its starting position and for urging said movable member into a front position in which the gears of said gear train mesh with each other, and means for moving said movable member to a back position for separating gears of said gear train in order that said resilient means may move said first named gear to its starting position.

2. A coin meter as defined in claim 1, in which said cam is coaxially turnably mounted on said first named gear, and a clamp screw mounted on

said first named gear holds said cam in adjusted position.

3. A coin meter as defined in claim 2, in which said cam has a coaxial slot through which said clamp screw passes.

4. A coin meter as defined in claim 1 in which a scale on said first named gear indicates positions of said cam for different timing periods.

5. A coin meter as defined in claim 1, in which 10 said resilient means comprises a single spring acting between said first named gear and said support.

HARRY GREENWALD.
